UNITED STATES PATENT OFFICE.

FRANZ FRÖHLICH, OF LEIPZIG, GERMANY.

REELING YARN UPON BOBBINS.

1,174,843.

Specification of Letters Patent. Patented Mar. 7, 1916.

Application filed November 4, 1915. Serial No. 59,616.

To all whom it may concern:

Be it known that I, FRANZ FRÖHLICH, a subject of the King of Saxony, and residing at Leipzig, in the German Empire, have 5 invented new and useful Improvements in Reeling Yarn Upon Bobbins, of which the following is a specification.

My invention relates to the art of reeling yarn upon bobbins; its object being to provide 10 a method by which the natural resiliency of the yarn can be preserved.

As spooling is now usually carried out, the rotating bobbin draws the thread of 15 yarn from the whisk, or cop, and thereby subjects the yarn to a certain stretching strain, the yarn being spooled in a tensioned condition. Owing to this strain the natural elasticity or resiliency inherent to 20 yarn is destroyed to a larger or lesser degree. It has been observed that this fact not only results in a decreased strength of 25 the yarn, but extends its influence in as far as yarn treated in this manner and used for manufacturing knitted or woven articles will yield less than yarn which is worked 30 up in unstretched condition. The explanation of this phenomenon lies in the fact that with stretched yarn elongated loops are obtained in which the arched portions are 35 cornered to some degree and, hence, more firm and unelastic. In consequence a larger quantity of yarn is required for the same article than if yarn is used which is in an unstretched condition when being worked 40 up and which is not deprived of its natural resiliency. Furthermore, experience has shown that yarn kept loosely upon the bobbin can be preserved, without any detrimental effect, for a longer period of time than 45 yarn which remains stretched after having been placed upon the bobbin. Because in the former case the natural resiliency of the 50 yarn is preserved and will not be lost during a longer period of time. The natural elasticity, or resiliency is, as a matter of fact, of influence also as regards strength and 55 durability of the looped fabrics manufactured from it; for since looped fabrics are particularly subjected to frequent stretching, the loops themselves will be less affected if the resiliency of the yarn material permits of a stretch to some degree.

The object of my invention is attained by 60 reeling the yarn upon the bobbin in the customary manner and then relieving the convolutions of the reeled or wound yarn 65

of the tension imparted to them during the reeling or winding operation immediately the bobbin is filled with yarn. This I accomplish by reducing or contracting the 70 inner seating surface of the wound yarn body, thus permitting each convolution to recede into an unconstrained condition by a movement of contraction. When yarn treated in this manner is worked up into 75 looped fabrics, the above mentioned advantages may then be turned to account.

The reduction or contraction of the inner seating surface of the wound yarn body can be accomplished in various ways. A preferred construction of a suitable bobbin which allows of readily reducing or contracting the inner seat of the wound or reeled yarn body is illustrated by way of example in the accompanying drawings in 80

Figure 1 shows the bobbin in elevation, while Fig. 2 is a sectional plan view taken on the line A—B in Fig. 1. Fig. 3 is a view similar to Fig. 1 but showing the contrivance for reducing or contracting the said seating surface in another position.

The barrel *a* of the bobbin adapted for the purpose of my invention, is provided with two longitudinal slots each of which is 85 dimensioned to receive two bars *d* and *c*; the bars *d* being fixedly mounted upon the bottoms of the slots. A bar *c* is pivotally connected to each of the bars *d* by means of links *e* which keep the bar *c* in parallel 90 relation to the adjoining bar *d* and permit the bar *c* to move toward and away from the fixed bar *d*. At one end the bars *c* are interconnected by pivotally jointed links *f*, *f*. When these links *f*, *f* are moved in the 95 direction of the arrow 1 in Fig. 1, the bars *c* are thereby caused to move away from the bars *d* till the links *e* have assumed a radial position as shown in Fig. 1. With the bars *c* in this position the bobbin is ready to be 100 filled with yarn.

The bobbin rotating, the thread of yarn will be passed around the bars *c* and a portion of the circumference of the bobbin barrel. When the reeling operation is completed, viz., when the bobbin is filled with 105 yarn, the jointed links *f*, *f* are drawn in the direction of the arrow 2 in Fig. 3, whereby the bars *c* are caused to move toward the bars *d* till they are within the circumference 110 of the bobbin barrel on which the wound yarn body will then be seated. The con-

traction of the seating surface entailing the above described favorable effect of relieving the convolutions of the wound yarn body of the tensional strain imparted to them during the winding or reeling operation.

While I have illustrated a suitable contrivance by means of which my novel method may be carried into effect, it is obvious that other means may be used instead and that 10 the scope of my invention is not limited to any specific means.

What I claim as my invention and desire to secure by Letters Patent of the United States, is:

15 1. The herein described method of preparing yarn for use in making knitted or woven articles comprising winding the yarn on a machine bobbin and then relieving said 20 yarn from the tension imparted to it while being wound on the bobbin, whereby dur-

ing the knitting or weaving operation it will be free from said tension.

2. A bobbin for knitting or weaving machines, comprising a core or body provided with oppositely arranged longitudinally extending grooves, a bar adapted to be received in each of said grooves and connected with the body so that it may be moved radially relative thereto, and a pair of links pivotally connected together and to adjacent ends of said bars for simultaneously moving them into or from said grooves, for the purpose described. 25 30

In testimony whereof I have hereunto affixed my signature.

FRANZ FRÖHLICH.
